UNITED STATES PATENT OFFICE.

FREEMAN W. HOOD, OF NORWICH, CONNECTICUT.

LOCK FOR FIRE-ARMS.

SPECIFICATION forming part of Letters Patent No. 241,804, dated May 24, 1881.

Application filed April 2, 1881. (No model.)

To all whom it may concern:

Be it known that I, FREEMAN W. HOOD, of the city of Norwich, and county of New London, of the State of Connecticut, have invented 5 a new and useful Improvement in Fire-Arms; and I do hereby declare the same to be described in the following specification, and represented in the accompanying drawings, of which—

10 Figure 1 denotes a side view, and Fig. 2 a longitudinal section, of a gun-lock and case provided with my invention, which, in part, is to effect rebound of the hammer from the nipple or firing-pin after each discharge of the piece, 15 the nature of my said invention being duly set forth in the claims hereinafter made.

In the drawings, A denotes the lock-case, which in this instance is a part of the stock of the gun or fire-arm.

20 B is the lock-hammer; C, its tumbler, and D the firing-pin.

E is the mainspring, which is fastened to the case, and is connected with the tumbler by a link, F, resting in notches *a b* made in the tumbler and spring.

25 Attached to the tumbler and hooked upon the lower part of the link is a small spring, *c*, whose object is to keep the link from accidentally getting out of place with respect to the tumbler and mainspring.

30 G is the trigger, arranged to operate with the tumbler in the usual manner.

Over the mainspring, and projecting down

from the case, is an abutment, H, against which the mainspring brings up just before the 35 hammer may strike the percussion-cap or firing-pin.

An auxiliary spring, I, fixed to the case and bearing on the tumbler back of the axis of its fulcrum, effects the rebound of the hammer 40 from the cap or firing-pin.

Were it not for the spring *c* the link would be liable, on stoppage of the mainspring by the abutment, to be thrown out of engagement with the tumbler and mainspring.

45 On the hammer being set to full-cock and the trigger being pulled, the said hammer, by the mainspring, will be thrown forward until the firing-pin may be struck, the spring being stopped in its advance by the abutment, and 50 the rebound of the hammer being effected by the auxiliary spring I.

What I claim as my invention is as follows:

1. The combination of the link-sustaining spring *c* with the hammer, tumbler, link, the 55 mainspring, and lock-case, arranged as set forth.

2. The combination of the link-sustaining spring *c*, the hammer, tumbler, link, mainspring, abutment, lock-case, and auxiliary or 60 rebound spring, all being arranged and adapted substantially as set forth.

FREEMAN W. HOOD.
